UNITED STATES PATENT OFFICE.

RALPH W. HUTCHENS, OF EAU CLAIRE, WISCONSIN, ASSIGNOR TO GILLETTE RUBBER CO., OF EAU CLAIRE, WISCONSIN, A CORPORATION OF WISCONSIN.

DESIGN FOR A TIRE TREAD OR SIMILAR ARTICLE.

Application filed August 13, 1925. Serial No. 14,410. Term of patent 3½ years.

To all whom it may concern:

Be it known that I, RALPH W. HUTCHENS, a citizen of the United States, and residing in Eau Claire, in the county of Eau Claire and State of Wisconsin, have invented a new, original, and ornamental Design for a Tire Tread or Similar Article, of which the following is the specification, reference being had to the accompanying drawings, forming a part thereof.

On the drawings:

I claim:

The ornamental design for a tire tread or similar article, as shown.

RALPH W. HUTCHENS.
